WEB FEEDING MECHANISM

Frank E. Weller, Bloomfield, N. J., assignor to
Trans-Lux Corporation, a corporation of Delaware

Application October 6, 1932, Serial No. 636,490
Renewed December 29, 1937

7 Claims. (Cl. 88—28)

My invention relates to mechanism for feeding or drawing a printed web through a projection field.

In an important respect, my invention relates to a combined web-feeding and tensioning arrangement for feeding the web through a projection field while maintaining the same taut and plane to insure highly satisfactory image projection.

10 My invention has further reference to novel features and characteristics of mechanism of the character stated whereby said mechanism may be efficiently and satisfactorily operated by a person of little skill.

15 Various other objects, advantages and characteristics of my invention will become apparent from the following detailed description taken in connection with the accompanying drawings.

My invention resides in the feeding mechanism, 20 arrangements and features of the character hereinafter described and claimed.

For an understanding of my invention and for an illustration of some of the forms thereof, reference is to be had to the accompanying drawings, in which:

Figure 1 is a side elevational view of mechanism as constructed in accordance with my invention;

Fig. 2 is a side elevational view of the mechanism of Fig. 1 but with various parts in different positions;

Fig. 3 is an enlarged vertical sectional view, partly in elevation, of mechanism as constructed in accordance with my invention;

35 Fig. 4 is a perspective view of a part of the mechanism shown in Fig. 3;

Fig. 5 is a plan view, with parts omitted, of a part of the mechanism shown in Fig. 3;

Fig. 6 is an elevational view, partly in section, 40 and is taken approximately on the line 6—6 of Fig. 3 looking in the direction of the arrows;

Fig. 7 is an elevational view, partly in section, and is taken approximately on the line 7—7 of Fig. 3 looking in the direction of the arrows;

45 Fig. 7a is a sectional view, partly in plan, of a part of the web-tensioning mechanism;

Fig. 8 is an elevational view illustrating a modification of the invention;

Fig. 9 is a plan view of a part of the mechanism shown in Fig. 8;

Fig. 10 is an elevational view, partly in section, and is taken on the line 10—10 of Fig. 9;

Fig. 11 is a vertical sectional view, partly in elevation, illustrating a modification of the invention;

Fig. 12 is a plan view, partly in section, of a part of the mechanism shown in Fig. 11; and

Fig. 13 is a vertical sectional view, partly in elevation, illustrating an arrangement for passing convection heat currents into contact with a section of the printed web.

In general, my invention relates to a combined printing device and projector, said device printing news items on a web which is moved through the projector to project images of the 10 printed characters on a display screen. Although combined devices of this general character are well known in the art, my invention is important because involving novel features contributing greatly to improved projection and simplification 15 of operation.

For a detailed description of my invention, reference is to be first had to Figs. 1 and 2, wherein C represents any suitable cabinet or housing having, as herein shown, a detachable or 20 movable door d. Disposed within the cabinet C is a projector P and a printing device D, the latter being movable to the exterior of the cabinet C as hereinafter more particularly described.

As more fully described in the copending Unkles 25 application Serial No. 325,551, filed December 12, 1928, and which has become U. S. Patent No. 2,018,691, dated Oct. 29, 1935. I represents a base or support which may be suitably secured to the bottom wall of the cabinet C. Rotatably 30 mounted on the base I is a turntable 2 which may carry a pivoted latch 3 coactable with a notch in the base I for retaining the parts in the normal position shown in Fig. 1, the latch 3 being releasable, however, so that the turntable 2 may be 35 rotated through an angle of 180 degrees into the position shown in Fig. 2.

Upstanding from the turntable 2 is a standard 40 4 on which the aforesaid projector P is supported in any suitable manner.

Pivoted to opposite sides of the turntable 2 are the lower ends of two pairs of legs 5, 5 and 6, 6, the upper ends of which are pivoted to a table 7. The latter carries a pair of spring-controlled latches 8, 8 which coact, respectively, with latch- 45 ing members 9, 9 carried by the standard 4. As clearly appears, the latches 8, 8 serve to retain the aforesaid pairs of legs in vertical position, Fig. 1, and, when said latches are released, said pairs of legs may be moved to inclined position as 50 shown in Fig. 2 to the extent permitted by one or more chains 10, or equivalent.

The printing device D, in the example herein shown, is of the type known to the art as a Dow-Jones printer. The printing mechanism 55

proper is detachably retained on the table 7 by a frame plate 11 secured in suitable manner to said table 7. Depending from the table 7 is a housing 12 for the motor and other operating parts of the printing mechanism.

As well understood in the art, the printing device D comprises spaced, upstanding plates in which is journaled a horizontal shaft 13, Fig. 3, carrying a type wheel 14 having characters distributed around the periphery thereof. The wheel 14 is freely slideable along the shaft 13 but is keyed thereto for rotatable movement therewith. Coactable with the type wheel 14 is an inking roller 15 to which ink is fed by a roller 16, ink being supplied to the roller 16 in suitable manner as well understood in the art. The rollers 15 and 16 are supported on a suitable frame 17 slideable on a rod 18 and with which the type wheel 14 together with said rollers 15 and 16 are movable as a unit in either direction longitudinally of the shaft 13. Coactable with the type wheel 14 is a platen or presser bar 19 which is normally biased to the position shown in Fig. 3 and which is intermittently actuated, as herein-after described, for printing purposes.

As shown in Figs. 1 and 2, a pair of the legs 5, 6 support a suitable bracket on which is mounted a reel 20 having a web W wound thereon. This web, in the example shown, is of suitable transparent or translucent material, such, for example, as Cellophane. From the reel 20, the web W extends upwardly between the type wheel 14 and platen 19, said web W further extending through the projector P as hereinafter to be described. After the printing wheel 14 has been rotated to a selected position, the platen 19 is actuated to thrust the web W into engagement with the selected character on said printing wheel.

The projector P comprises a housing 21 suitably supported on the standard 4, said housing having disposed therein a lamp bulb 22 or other suitable source of illumination. Light from the lamp 22 emerges as a light beam through a lateral opening 21a in the housing 21.

Arranged in horizontal alignment with the aforesaid opening 21a is a light passage formed by a bottom wall 23 and spaced side walls 24 and 24a, these walls forming a single casting which is suitably secured to the lamp housing structure. Disposed in the light passage thus formed are a pair of condenser lenses 25, 25a which are detachably retained in operative position in suitable manner, as by the transverse rod 26 and spring members 27.

Transversely arranged with respect to the side walls 24, 24a is a front wall 28, Figs. 3 and 7, which forms a part of another casting suitably secured to the casting which comprises the walls 23, 24, 24a and which is provided with an aperture 28a forming the projection field of the herein described projection mechanism, the condenser lens 25 also abutting said wall 28 as clearly shown in Fig. 3.

As illustrated particularly in Fig. 3, the aforesaid front wall 28 comprises upper extensions 29 at the respective opposite sides thereof, each of these extensions terminating in a pair of spaced ears 30, 30a, Fig. 7.

The extensions 29 of the front wall 28 form bearings for a transverse shaft 31 on which a plurality of spaced rollers 32 are mounted for rotatable movement therewith. As shown particularly in Fig. 5, it is desirable that each of the rollers 32 be provided with peripheral rows of corrugations along the respective opposite sides

thereof, these rows of corrugations being separated by a channel disposed centrally thereof.

Depending from the aforesaid bottom wall 23 are a plurality of spaced ears which support a transverse rod 33, Fig. 3. Mounted on the rod 33 for free oscillatory movement are a plurality of spaced fingers 34 which extend in parallel relation beneath the wall 23, Figs. 3 and 7a, each finger 34 terminating in an inclined surface as shown in Fig. 3. The fingers 34 are positively biased for movement in a counter-clockwise direction, Fig. 3, and, to this end, it is desirable that each finger be formed with an offset mass of material 34a of sufficient weight to obtain the desired biasing effect. To prevent the operative ends of the fingers 34 from dropping unduly, it is desirable for each finger 34 to comprise a section 34b through which is threaded a screw 35 coactable with the lower surface of the wall 23, Fig. 3.

Referring particularly to Figs. 3, 5 and 6, there is shown a frame 36 which, along each side thereof, comprises a pair of spaced ears 37, 37a so arranged that one pair thereof fits snugly between one pair of the ears 30, 30a while the other pair thereof fits snugly between the other pair of the ears 30, 30a. As shown on the drawings, a screw 38 is threaded through the pair of ears 30, 30a at the left, Fig. 7, and the pair of ears 37, 37a which are registered therewith. It results, therefore, that the frame 36 may be swung clockwise from the full to the broken line position of Fig. 5 about the screw 38 as an axis. The frame 36 may positively be retained in the full line position of Fig. 5 by a screw 39 threaded in the ear 30 as shown at the right of Fig. 7.

In accordance with my invention, the screws 38 and 39 may be interchanged from the respective positions shown in Fig. 5. If this is done, the frame 36 may be swung from the full to dot-and-dash line position of Fig. 5 about the relocated screw 38 as an axis. The advantage of this feature will be hereinafter pointed out.

Mounted in upstanding lugs 40, 40a of the frame 36 is a rod 41 on which a plurality of rollers 42 are mounted. These rollers 42 comprise sections 42a which coact, respectively, with the aforesaid rollers 32 and each roller 42 also comprises sections 42b which gives weight thereto. As clearly illustrated in Fig. 3, the rollers 42 are loosely mounted on the rod 41 whereby they are biased in a downward direction for a reason hereinafter to be stated.

The aforesaid frame 36 comprises sections 36a, 36a extending downwardly outside of the path of the projecting light beam, said sections carrying a journaled shaft 43 having a plurality of spaced wheels 44 mounted thereon for rotatable movement therewith. Preferably, as illustrated, the wheels 44 are edged and they are so spaced that each wheel 44 coacts with one of the aforesaid fingers 34.

Secured to the frame 36 is a bracket 45 formed in part as an annulus for the reception of the casing 46 of an objective lens. The bracket 45 also comprises depending sections which carry a plate 47 on which a mirror 48 is suitably secured, as by the spring clips 49.

In order to place the herein described projector mechanism in condition for operation, the frame 36 is swung on the pivot 38 until said frame together with the parts carried thereby are moved into the position shown at the left of Fig. 5. A length of the web W is then drawn through the printing device D and laid against the plate 28, 75

said web resting on the rollers 32 and projecting therebeyond. The frame 36 is then returned to the full line position illustrated in Fig. 5 and the screw 39 placed in the position shown to positively 5 lock said frame in operative position. In so doing, the rollers 44 move against a transverse section of the web W which is gripped between said rollers and the fingers 34. At the same time, the roller sections 42a come into coacting relation 10 with the respective rollers 32 whereby a second transverse section of said web is gripped.

Preferably, as shown in Figs. 1, 2 and 13, an area of the top wall of the cabinet C, above the lamp housing 21, is provided with the slots or 15 passages 50. The web W is passed through this top cabinet wall C and arranged in overlying relation with respect to this slotted area, said web extending beyond the cabinet and hanging down at one side thereof as clearly shown in Figs. 1 20 and 2.

The mechanism with the web W properly positioned therein for the printing and projecting operations is shown in Figs. 1 and 3. The printing mechanism D, as hereinbefore described, comprises the printing wheel 14 which moves step-by-step along the shaft 13 transversely of the web W, while the latter is stationary, to print a line of information thereon. At the conclusion of 25 each line-printing operation, the printing wheel 14 is automatically returned to its initial position and, simultaneously, a step of movement is imparted to a train of gear mechanism which includes the gears 51 and 52, Fig. 3. The gear 52 is carried by a stub shaft 53 rotatably mounted 30 in a bracket 54 carried by a rod 55 secured to the frame of the printing device D, the bracket 54 being maintained in the proper adjusted position on the rod 55 by a screw 56. The shaft 53 is operatively connected to the shaft 31 and, preferably, a flexible shaft 57 is thus utilized, one end 40 of the shaft 57 being connected to the shaft 53, Fig. 4, and the other end of said shaft 57 being connected to the shaft 31, Fig. 7.

The rollers 32 are mounted on the shaft 31, the 45 web W being gripped between these rollers and the roller sections 42a. Accordingly, it results that each return of the printing wheel 14 to its initial position effects actuation of the rollers 32 whereby a step of movement is imparted to the web W, the 50 gear ratio being so chosen as to obtain the desired spacing between the printed lines. As shown in Figs. 1 and 2, the web W extends over the slotted cabinet area 50 and hangs down beside the front cabinet wall. The action of gravity on this hanging web section tends to keep the web relatively 55 taut back to the wheels 42.

It follows, therefore, that the web W is moved 60 upwardly step by step to bring the successive lines of printed matter into the projection field, i. e., the field defined by the aperture 28a of plate 28. Light from the lamp 22 passes from right to left, Fig. 3, through the condenser lenses 25, 25a, through the aperture 28a, and then through the 65 web section defined by said aperture, the light beam thereafter engaging the mirror 48 and being deflected vertically upward through the objective lens 46, said light beam thereafter passing to any suitable reflecting system and screen, not shown, where images appear of the tape characters then 70 on the web section in the projection field 28a. These images remain stationary on the screen while the web remains stationary but, each time that the printing wheel 14 returns to its initial position, the printed lines on the web are stepped 75

upwardly to thereby impart corresponding movement to the lines of images on the screen.

An important feature of my invention involves the passage of the web W exteriorly of the casing C and over the grooves 50. Heated air from the 5 lamp 22 ascends through these grooves and contacts with the overlying web section to effect rapid drying of the ink thereon. This is advantageous because permitting the web section beyond the 10 grooves 50 to be handled without smudging the inked characters thereon.

Another important feature of my invention relates to the disclosed arrangement for transversely gripping the web W at spaced points both above and below the projection field. It is highly 15 important for that web section in the projection field at any given time to be substantially taut and plane in configuration, i. e., un wrinkled and undistorted. This, in accordance with the present invention, is accomplished in a highly desirable 20 manner.

Immediately below the projection field, the web W is gripped at spaced points thereacross by the rollers 44 and the fingers 34 which coact, respectively, therewith, the offset weights 34a on each 25 of the fingers 34 functioning to bias the latter toward the rollers 44 with sufficient force to grip the web W in the desired manner. It follows, therefore, that equal restraining forces are applied to the web W at spaced points thereacross 30 and it is against these forces that the web is pulled upwardly by the rollers 32. The latter together with the roller sections 42a also grip the web at spaced points thereacross and, in an even manner, move the web upwardly against the restraining force applied thereto by the fingers 34. 35 In practice, it has been demonstrated that a web-restraining and -pulling arrangement of the character just described is highly advantageous and efficient because maintaining the web section in 40 the projection field plane and even with resultant highly satisfactory projection. The provision of the edged rollers 44 is highly important because these rollers coact with the freshly inked surface of the web W. However, since these rollers are of 45 knife-edge configuration, little or no smudging of the ink occurs.

The use of weights, i. e., the finger sections 34a and the roller sections 42b, gives improved results 50 compared with the spring arrangements which heretofore have been generally utilized for biasing purposes. The heat generated by the projection lamp and other adverse factors cause the force of a biasing spring to vary or change from time to time. The biasing effect of the above described 55 weights, however, is constant and invariable.

Another important advantage of the herein described invention relates to the arrangement whereby the frame 36 together with the parts carried thereby may be swung to one side when it 60 becomes necessary to re-thread the web through the projector field or otherwise service parts of the machine. By virtue of the disclosed arrangement, the web re-threading operation is extremely simple and readily performable even by an unskilled worker.

A further feature of importance relates to the interchangeability of the pivot pin for the frame 36. Accordingly, it follows that said frame may be moved to either of the broken line positions 70 illustrated in Fig. 5, it being necessary simply to reverse the respective positions of the screws 38 and 39 as desired. It may be desirable thus to interchange these pivot screws due to some local condition arising in connection with a particular 75

installation which might prevent pivotal movement of the frame 36 in one direction while permitting free pivotal movement in the other direction.

In Fig. 2, I have illustrated the printing mechanism D in the servicing position thereof. The door d of the cabinet C has been removed and the turntable 2 has been rotated through an angle of 180 degrees. Thereupon, after release of the latches 8, the printing mechanism is swung on the legs 5, 6 to the extent permitted by the chains 10. It will be observed that the flexible shaft 57 is of such length that the described movement of the printing device D to servicing position may be effected without interfering with the driving connection between said printing device and the web-pulling rollers 32. This obviously, is a distinct advantage. After the printing device D has been returned to normal position, the web section exteriorly of the cabinet may be grasped to pull the web through the projection field until the slack has been taken up and, thereafter, the normal printing and web-pulling action occurs.

Referring to Figs. 11 and 12, there is illustrated a modified arrangement for biasing the web into engagement with the rollers 44. Thus, in lieu of the fingers 34, there is utilized a bar 60, the length of which is about the same as the width of the web W. The bar 60 is pivoted for movement in a horizontal plane to a second bar 61 which at one end projects beyond the wall 24 and at its other end projects beyond the wall 24a. Pivoted exteriorly on each of the walls 24 and 24a is a bell crank lever 62 which comprises an offset weight section 62a, the levers 62 being suitably connected to the respective opposite ends of the bar 61.

The levers 62 tend to move in a clockwise direction, Fig. 12, whereby the bars 61 and 60 are biased in a direction from right to left, Figs. 11 and 12. The bar 60 comprises a sloping surface and maintains the web W against the rollers 44 with the required degree of pressure, the pivotal mounting for said bar 60 permitting the same to assume the proper operative position with respect to the rollers 44. The arrangement of Figs. 11 and 12 as thus described gives satisfactory results although the arrangement involving the fingers 34, at present, is preferred thereto.

In Figs. 8 and 9, I have illustrated a modification of the invention as regards the driving connection between the printing device D and the projector mechanism P. As shown, the member 55 supports a bracket 70 which carries a stub shaft 71 having secured thereto a cam 72 together with a gear 73 which meshes with the aforesaid gear 51. Pivoted on the bracket 70 is a frame 74 carrying a cam follower 75 and a mercury switch 76, the frame 74 being biased by a spring 77 in a clockwise direction, Fig. 8, whereby the follower 75 is maintained in engagement with the cam 72. Leading from the switch 76 is a cable comprising a pair of conductors which lead to the respective terminals of a solenoid 78, said cable including the plug 79 which is readily detachable from the socket 80 for opening the circuit to the solenoid 78. The solenoid 78 may be mounted on the exterior surface of the wall 24 and is utilizable for actuating a lever 81 which terminates in a gear segment 82 disposed in meshing relation with respect to a gear wheel 83 loosely mounted on the aforesaid shaft 31. Rotatable with the gear wheel 83 is a disk

84 to which is pivoted a pawl 85 coactable with a ratchet wheel 86 rotatable with said shaft 31.

As clearly appears in Fig. 8, the cam 72 is of the double-surface type and, as shown in this figure, the cam is in one of its normal positions. The gear ratio of the train of mechanism leading up to the gears 51 and 73 is such that each actuation of said train of mechanism, as effected by the return of the printing wheel 14 to its initial position, causes the cam 72 to rotate through an angle of 180 degrees.

It follows, therefore, that when said printing wheel 14 returns to its normal position as stated, the cam 72 is rotated counter-clockwise, Fig. 8, through an angle of 180 degrees. As a result, the switch 76 is tipped in a clockwise direction, Fig. 8, and the circuit through the solenoid 78 is closed. Accordingly, the lever 81 is moved in a counter-clockwise direction, Fig. 8, to thereby impart a rotatable step of movement to the shaft 31 while the web W is correspondingly moved through the projection field.

Movement of the cam 72 through the angle of 180 degrees occurs almost instantaneously and, as will be obvious, the switch 76 is immediately returned to the position shown in Fig. 8. As a result, the circuit through the solenoid 78 is re-opened and the lever 81 returns to the position shown, the pawl 85 idling with respect to the ratchet wheel 86. The mechanism is now in condition to impart the next feeding impulse to the web W which occurs, in the manner described, as soon as the printing wheel 14 again returns to its initial position.

When the application of energy to the shaft 31 is discontinued in response to deenergization of the solenoid 78, there occurs some reverse movement of the shaft 31 in a counter-clockwise direction, Fig. 8, unless special mechanism is provided to prevent such reverse movement. Mechanism for this purpose is illustrated in Figs. 9 and 10.

As shown, a housing 95 is suitably secured to the extension 29 of the wall 24 and this housing has a disk 94 rotatable therein, the disk 94 being secured to the shaft 31 for rotatable movement therewith. The housing 95 comprises a passage having therein a ball 93 biased by a spring 90 into engagement with the edge of the disk 94.

When the shaft 31 is moved in web-feeding direction by the pawl 85, it moves in a clockwise direction, Fig. 10. During such movement of the shaft 31, the disk 94 merely thrusts the ball 93 against the spring 90. However, as will be obvious from Fig. 10, the ball 93 functions as a locking dog and positively prevents counter-clockwise movement of the disk 94 and the shaft 31 which is connected thereto.

Since the ball 93 and disk 94 function as just stated, it results that the shaft 31 does not recede, even slightly, from the position to which advanced by the pawl 85. This is highly desirable because preventing the occurrence of sag of the web section in the projection field. Should this web section sag, the resultant projection is more or less unsatisfactory due to poor image focus.

Use of the mechanism last described, namely, the housing 95, disk 94, ball 93 and spring 90 is highly desirable with all forms of my invention. Hence, in Fig. 7, I have illustrated such mechanism as applied to the shaft 31 to prevent receding movement thereof after the application of energy to the shaft 57 has been discontinued.

With an arrangement of the character described in Figs. 8 and 9, it is necessary merely to 75

detach the members 79 and 80 when the printing device D is to be moved to a position such as shown in Fig. 2.

In the appended claims, it shall be understood that the expressions "means for printing," "printing device," or equivalent expressions generically comprehend a Dow-Jones or other printer, or any equivalent arrangement such, for example, as a typewriter utilizable for producing or forming characters in line form transversely of a traveling web.

While the invention has been described with respect to certain particular preferred examples which give satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. Projection apparatus comprising a projection field with respect to which a character-bearing web is movable, a frame, optical structure carried by said frame, and means forming pivotal axes for said frame at opposite sides, respectively, of said projection field.

2. Projection apparatus comprising a projection field with respect to which a character-bearing web is movable, a frame, optical structure carried by said frame, and means forming vertical pivotal axes for said frame at opposite vertical sides, respectively, of said projection field.

3. Projection apparatus comprising a projection field with respect to which a character-bearing web is movable, a frame, an objective lens and a light-reflecting mirror carried by said frame, and means forming vertical pivotal axes for said frame at opposite vertical sides, respectively, of said projection field.

4. Projection apparatus comprising a projection field with respect to which a character-bearing web is movable, sets of coacting rollers at one side of said projection field for drawing said web

therethrough, coacting sets of elements at the other side of said projection field for applying a retarding force to said web, a frame carrying one set of said rollers and one set of said elements, and means for movably mounting said frame whereby the set of rollers and elements carried thereby may be moved aside when it becomes necessary to position the web in said projection field.

5. Projection apparatus comprising a projection field with respect to which a character-bearing web is movable, means for drawing said web through said projection field, and means for retarding the passage of said web through said projection field, said last named means comprising a plurality of rollers engaging said web at spaced points thereacross, said last named means also comprising fingers coactable, respectively, with said rollers for engaging the web therebetween.

6. Projection apparatus comprising a projection field with respect to which a character-bearing web is movable, means for drawing said web through said projection field, and means for retarding the passage of said web through said projection field, said last named means comprising a plurality of rollers engaging said web at spaced points thereacross, said last named means also comprising gravity-biased fingers coactable, respectively, with said rollers for engaging the web therebetween.

7. Projection apparatus comprising a projection field with respect to which a character-bearing web is movable, sets of coacting rollers at one side of said projection field for drawing said web therethrough, coacting sets of elements at the other side of said projection field for applying a retarding force to said web, a frame carrying one set of said rollers and one set of said elements, a mirror and an objective lens carried by said frame, and means for movably mounting said frame whereby the set of rollers and elements together with the mirror and lens carried thereby may be moved aside when it becomes necessary to position the web in said projection field.

FRANK E. WELLER. 45
